INTERPUPILLARY DISTANCE GAGE

Thomas L. Hermann, West Henrietta, N.Y., assignor to
Bausch & Lomb Incorporated, Rochester, N.Y., a cor-
poration of New York

Filed Mar. 26, 1965, Ser. No. 84,453

Term of patent 14 years

(Cl. D57—7)

FIG. 1

FIG. 2

FIG. 1 is a top perspective view of the interpupillary distance gage taken from one end thereof showing my new design; and

FIG. 2 is a bottom perspective view of said gage taken from the opposite end thereof.

I claim:

The ornamental design for an interpupillary distance gage, substantially as shown.
